GRILLEWORK FOR TREILLAGES OR THE LIKE

Robert F. Seery and John A. Ward, Louisville, Ky., assignors to Julius Blum & Co., Inc., a corporation of New York

Filed Apr. 10, 1959, Ser. No. 55,448

Term of patent 14 years

(Cl. D54—2)

Fig. 1 is an elevational view of a grillework for trellises or the like, showing our new design, it being understood that the flower-like members and the circular connecting stems have the forms throughout the design as shown,

Fig. 2 is an enlarged sectional view taken on line 2—2 of Fig. 1,

Fig. 3 is an enlarged transverse sectional view, taken on line 3—3 of Fig. 1, and

Fig. 4 is an enlarged transverse sectional detail view taken on line 4—4 of Fig. 1.

We claim:

The ornamental design for a grillework for trellises or the like, substantially as shown and described.
